UNITED STATES PATENT OFFICE

FRED M. CARROLL, OF YONKERS, NEW YORK, ASSIGNOR TO THE TABULATING MACHINE COMPANY, OF ENDICOTT, NEW YORK, A CORPORATION OF NEW JERSEY

TABULATING MACHINE

Application filed July 20, 1928. Serial No. 294,089.

The present invention relates to accounting machines and more particularly to improvements in record card controlled machines whereby the latter may be used in connection with various types of record cards.

Record-card controlled machines have been designed to operate in response to either regular Hollerith cards wherein a single index point perforation by its location determines the differential adjustment of data indicating devices, or in response to cards designated as "combinational hole" cards. In the latter type of cards either a single index perforation or different combinations thereof constitute the data controlling means and such cards are, comparatively speaking, preferable since they permit a greater amount of data to be placed upon the card for a given area. Various types of machines employing combinational hole cards have been designed, such as, for example, that disclosed in the copending application of F. M. Carroll, Serial No. 185,711, filed April 22, 1927, now Patent No. 1,726,539, and while such machines would increase the efficiency of systems now in use they would be of little value to firms now operating Hollerith tabulating machines since they would not permit the employment of regular Hollerith punched cards. This objection, of course, could be readily overcome by re-punching cards to convert them to combinational hole designations but such a procedure would entail considerable expense and time far outweighing any advantages accruing from combinational record-card controlled machines.

It is then a broad object of the present invention whereby combinational record card controlled machines may be readily converted so as to be responsive to Hollerith cards.

It is a further object whereby selecting means may be provided to adjust a tabulating machine to render the various mechanisms therein responsive to either combinational or Hollerith record cards.

Another object of the invention is to provide means for suspending the operation of the device which permits combinational hole record cards to select numeral and alphabet type for printing whereby perforations in

regular Hollerith cards may select numeral type only during listing operations.

It is still a further object to convert the analyzing or translating mechanisms of a tabulator to render the same responsive to either combinational or Hollerith record cards.

It is still a further object of the present invention to selectively alter the card feeding mechanism of a tabulator to provide for feeding various forms of record cards which differ dimensionally in hole spacings whereby either may be fed in proper synchronism with other controlling mechanisms.

While the particular improvements set forth are shown in connection with the particular type of machine disclosed in Serial No. 185,711 to accomplish the broad objects enumerated it is to be understood that with slight modifications the improvements may be applied to other forms and types of machines with equally beneficial results, and that the present invention should be considered illustrative rather than restrictive.

The invention may be clearly understood from the following detailed description which should be read in connection with the accompanying drawings, in which the same parts are identified by the same numerals throughout the several views and in which

Fig. 1 shows diagrammatical representations of the mechanical elements of a complete machine;

Fig. 2 shows the circuit diagram of the machine;

25 Figs. 19, 20 and 21 are details of the translating mechanism showing the parts in different positions.

General description

30 Referring first to Fig. 1 the motor for driving the machine elements is shown at 50 and is connected by a belt and pulley to a gear train indicated generally at 51 and which through suitable extensions operates the tabulating shaft 52, the shaft 53 on which the jacks for the switch bars and automatic control restoring mechanism and the regular cam contacts are mounted and shafts 54 and 55, the former of which operates the total timer 56 and the translating elements 57 and the latter of which operates the starter timers 58 and 59. The printing drum 61 and the platen 62 are likewise driven from the gear train 51. The shafts 53, 54, 55 and the drum 61 rotate constantly as long as the motor 50 is in operation.

35 The card feed clutches, enclosed in the clutch box 63, are driven from the shaft 53. As will be hereinafter explained, the card feed mechanism is driven from clutches through a gear train 156 and the clutches are so arranged that certain types of cards will be fed to the analyzing mechanism every fourth cycle as long as the card feed clutches are in operative position and regular Hollerith cards every machine cycle. That is, certain types of cards will be fed to the analyzing mechanism during one cycle and the card feed will then be suspended during the two following cycles and regular Hollerith cards will be fed every machine cycle. The machine requires certain card feed cam contacts to be closed every cycle and certain other card feed cam contacts closed every three cycles. The machine is provided with a switch bar 700 called the adding and listing switch bar. The adding and listing switch bar serves to connect the accumulators and printing call magnets with the analyzing mechanism or brushes

during adding and listing cycles. The adding and listing switch bar is shown in open circuit position. The adding and listing switch bar is controlled from a jack 81 which consists of a cam 82 mounted on shaft 53. As the shaft rotates the cam permits a rod 83 to rise and release the bell crank lever 84 thereby permitting a spring 85 to move the switch bar 700 to circuit closing position during the tabulating and listing portion of each machine cycle.

50 The timers 56, 58 and 59, driven by the shafts 54 and 55, consist essentially of a group of cam operated contacts whose function is to close certain controlling circuits at certain predetermined times during machine operation. These timers do not operate constantly but only when the card feed is initiated and during total taking operations. The timers 58 and 59 control the starting of card feed and the timer 56 controls total taking. Each of these timers when set into operation is operative for six machine cycles to control contacts as will be hereinafter described.

55 The tabulating shaft 52 drives the several counter elements 120 of the machine. Each counter element (see Fig. 8) is provided with an individual driving shaft 121 geared to the tabulating shaft through bevelled gear 122 and bevelled pinion 123 and constantly rotated thereby. Fixed on the shaft 121 is a clutch member 124 and freely mounted on the shaft 121 is a slidable member 125 which corresponds to the usual counter element of accumulators. The members 124 and 125 have cooperating clutch teeth on their adjacent faces and when the counter element 125 is shifted to bring its clutch teeth into engagement with those on the member 124 the member rotates with the shaft 121. The shifting mechanism consists of a lever 126 which is urged by a spring 127 to constantly force the member 125 into clutching engagement with a member 124. This shifting action is normally prevented by latch 128 whose end is under an arm on the shift lever 126. Energization of the counter magnet 130 attracts its armature 131 and an extension 132 thereon rocks the latch 128 from beneath the arm of shift lever 126. The lever thereupon shifts the member 125 into engagement with the member 124. A lug on a sleeve member 133 fixed to the shaft 121 engages the shift lever 126 at a predetermined point in the cycle and rocks it into latching position disengaging the counter element 125 from the driving element 124. The magnet 130 is energized in response to perforations on a controlling record and the clutch kick-out is timed so that the movement of the counter element 125 corresponds to the number represented by the perforation. The mechanisms thus far described are common to the printing tabulator disclosed in the copending application referred to above, to which ref-

erence should be had for a complete explanation of them. They have been described very briefly in the present case merely to aid in an understanding of the present invention.

5 The card feed mechanism has been modified to conform to the peculiar operation of the machine which makes it necessary to suspend the card feed during certain operative printing cycles for certain types of cards and 10 to permit feeding of regular Hollerith cards during every machine cycle. Other improvements have also been incorporated in the card feed, for example, the feeding mechanism is arranged to provide for the different 15 spacing of the index point designations on the different types of cards used to control the machine.

Referring to Fig. 3 the card magazine having a stack of cards therein is indicated at 160, 20 and the discharge rack directly below it at 161. The cards are fed from the magazine 160 by a picker 162 which is operated by an oscillating lever 163 driven by a connecting rod 164 whose end distant from the lever 163 25 is eccentrically pivoted on a gear wheel 165 attached to a shaft 165a which is driven during one cycle and remains idle during the two following cycles or is driven once every machine cycle as will hereinafter be explained. 30 As the picker oscillates it feeds the lower card of the stack in the magazine to a set of feed rolls 166, likewise driven by the gear 165, passing the card successively to the control analyzing brushes 167 and the adding analyzing 35 brushes 168. It will be noted that two control brushes and two adding brushes have been provided for each card column. The character code making use of a combinational system of perforations of the type of card shown in Fig. 6 requires much less card space 40 than the system in which each character is represented by a single perforation (as exemplified in Fig. 7) and the numerals and alphabet under the combinational system can be compressed into a card field about half the 45 width of that necessary in the single perforation system. It is quite possible therefore to provide two card fields one below the other on the type of tabulating card shown in Fig. 50 6 which is of the usual size so that different items may be independently represented on these two fields.

The two brushes in each pair 167 and 168 are spaced apart so that as a card feeds under them, one of the brushes cooperates with an index point position in one field of the card while the other cooperates with the corresponding index point position on the other card field; that is, as the card passes under the brushes one brush analyzes one field while the other brush analyzes the other at exactly the same time. Items on the two card fields may thus be entered into different accumulators or printed on different printers. 65 The brushes, as usual, cooperate with con-

ducting cylinders shown at 169 for the brushes 167 and at 170 for the brushes 168. The machine is provided with the usual card lever contacts which are shown at 172 for the adding brushes 168. These contacts are closed 70 whenever a card is under the brushes 168 by a bail 173 which is operated through a rod 174 pivoted to a pivoted arm 175 of which an extension 176 extends into the path of a portion of the card being analyzed. A card 75 in passing rocks the extension 176 of the lever 175 counterclockwise, pulling the rod 174 to the right as shown in the figure and rocking the bail 173 to close the contacts 172.

The path of the cards in feeding is indicated by the dot-dash line and each card after passing through the upper set of rolls is delivered to a lower set of feed rolls 180 which are driven from the drive mechanism of the upper rolls. A pivoted member 181 is rocked 80 during each card feeding cycle by a cam 182 also driven from the gear train driving the feed rolls and the movement of the member 181 is timed so that as the card feeds along the conveyor system its edge eventually encounters the member 181 and shortly after the cam rocks the member 181 forcing the card to the lower rolls 180 which eventually deliver it to the discharge rack 161. A positive feed is provided for forcing the card from the last set of lower rolls 180 in the form of a member 184 which is operated to engage the trailing edge of each card through a link 185 and cam 186. 95

Card feeding devices

The mechanism for operating the card feed mechanism for the combinational hole cards represented by Fig. 6 will now be explained in connection with Figs. 9 to 12, inclusive. 105 Referring to Fig. 9, the shaft 53 (see also Fig. 1) rotates constantly while the drive motor is in operation, making one revolution for each machine cycle. The card feed mechanism including the picker and the feed rolls, just described is driven from the shaft 191 mounted in alignment with the shaft 195 and driven therefrom through a one revolution clutch. The shaft 53 through one to one gears 192 and 193 drives one element 196 110 of a one revolution clutch freely mounted on shaft 195. The other element 198 of this clutch is fixed to the shaft 195 and clutching engagement between the elements 196 and 198 may be effected by a card feed clutch magnet in which case shaft 195 rotates revolution for revolution with the constantly rotating shaft 53. The shaft 195 must drive the card feed shaft proper 191 under two different conditions; first, when the machine is started with no card under its upper brushes, in which case the first card will feed from the card magazine to the upper brushes during one machine cycle and from the upper to the lower brushes during the succeeding cycle; 115 120 125 130

and second, when successive cards are feeding past the lower brushes in which case each successive card must feed to the lower brushes during one machine cycle and card feed must then be suspended during the two following cycles. The shaft 195 has the driving element 205 of a second one revolution clutch fixed to it of which the driven element 206 is fixed to the shaft 191 (see also Fig. 10). This clutch is normally engaged and consequently when the machine is put into operation with no card under the upper brushes the shaft 191 will make two revolutions with the shaft 195 feeding the first card first under the upper brushes and then under the lower brushes during successive machine cycles. When the first card reaches the lower brushes of course the second condition prevails and card feed must now be suspended for two machine cycles after another card is fed to the lower brushes and analyzed.

The shaft 195 carries a gear 199 which meshes with a gear 200 fixed to a sleeve 208 freely mounted on shaft 201. The gear ratio in this case is one to three so that sleeve 208 makes one revolution for every three revolutions of the shaft 195. Also fixed to the sleeve 208 is a driving element 202 of a third one revolution clutch whose driven element 203 is fixed on shaft 201. This clutch is controlled by a secondary card feed clutch magnet which is energized only when there is a card under the upper brushes and the clutch 196-198 is in operation. When this third clutch engages the shaft 201 rotates with a one to three ratio with shaft 195. A cam 239 through suitable linkage then insures that when the clutch 196-198 is once engaged it will remain engaged for three machine cycles or revolutions and a cam 252 through suitable linkage causes the clutch 205 to engage during one machine cycle and to disengage during the two following cycles. This complete operation will be more fully described in connection with the following explanation of the clutch mechanical details and in the explanation of the circuit diagram.

The details of the clutch mechanisms will now be described. Referring to Fig. 12 the one revolution clutch for driving the shaft 195 from the shaft 53 consists of a disc 196 rigid with the gear 193 and having a notch 211 of a peculiar form in its periphery. This disc, of course, is free on shaft 195 and rotates whenever the shaft 53 rotates. The second element 198 of the clutch fixed on shaft 195 carries a pivoted operating pawl 212 urged by a spring to constantly engage in the notch 211 but normally restrained from doing so by a latch 213. The latch 213 is mounted on one element 225 of a toggle indicated generally at 214, the element 225 being fixed to a shaft 231 to which is also fixed an extending arm 215 having a hooked portion 216 at its upper end which is engaged

by a coacting hook on the pivoted structure supporting the armature 217 of the card feed clutch magnet 218. The other element of the toggle consists of an arm 234 pivoted on a shaft 262 and connected with the element 225 by a pin and slot connection.

Fixed to the shaft 262 (see also Fig. 11) is a member 227 having a double bevelled upwardly extending portion projecting into the path of the tail piece of the pawl 212. The member 227 is also provided with a notch 232 which straddles a shaft 229 and limits the movement of the member. A light spring 235 urges the member 227 counterclockwise holding the lower edge of the notch 232 against shaft 229. Energization of the magnet 218 attracts its armature 217, rocking the pivoted armature supporting structure and releasing the arm 215 which moves counterclockwise in response to the action of spring 219. The toggle 214 breaks causing the latch 213 to release the pawl 212. The pawl then rocks clockwise under action of its spring and its nose moves to the bottom of notch 211 in moving member 196, while its tail piece snaps past the bevelled end of member 227, the biasing spring of the latter yielding to permit this action. The trailing edge of the notch 211 as indicated at 220 consists of a smooth curved surface terminating at the periphery of the disc in a slightly undercut portion 233. As the disc 198 on which pawl 212 is pivoted still tends to remain stationary, the curved surface 220 on the moving disc 196 cams the pawl counterclockwise forcing its tail piece against the left hand bevelled surface on the upper end of member 227, thereby forcing the disc 198 in a clockwise direction, that is, in the same direction as the disc 196 is moving. Owing to the configuration of the curved surface 220 this camming action on the pawl starts the disc 198 rotating with a gradually increasing speed and when the nose of the pawl reaches the undercut portion 233, clutching the discs together, the two discs 196 and 198 are moving at substantially the same speed and the clutching operation has been effected with no shock to the several parts. When the nose of the pawl engages the undercut portion 233, a latch pawl 221 on the disc 198 slips into the notch 211 and engages a flat edge 222 of the notch, firmly locking the members together in a predetermined relative position. The shaft 195 is now rotating with the shaft 53 and will continue to do so until the pawl 212 is again latched by latch 213. The latter, of course, has been moved out of the path of the extending tail piece of the pawl by the breaking of the toggle 214 and cannot reengage the pawl until the toggle is restored to the position shown in Fig. 12. As previously stated when the magnet 218 is once momentarily energized during normal running of the machine, it is necessary that

the shaft 195 rotate for three revolutions. Once each revolution a pin 223 on disc 198 encounters an offset portion 224 on member 215 and rocks it clockwise to its latching position. This restores the toggle and if the pivoted supporting structure of armature 217 is in latching position at this time, its hook will engage the hook 216 on member 215 and hold toggle 214 in its restored position as in Fig. 12. During the two machine cycles following that in which the magnet 218 is energized, however, the armature structure is rocked clockwise to its inoperative or unlatching position by a cam 239 on shaft 201 coacting with a pivoted cam follower 238 to which is pivoted the upper end of a link 237 whose lower end is pivoted to a lever 236, fulcrumed on the supporting shaft of the armature structure. The shaft 201 as previously explained is driven from the shaft 195 during normal running card feed with a one to three ratio both clutches 196-198 and 202-203 (Fig. 9) being engaged. During the first portion of the initial cycle in which the magnet 218 is energized the cam follower 238 rides on the lower concentric surface of cam 239 and hence has no effect on the latching mechanism. Shortly after the member 215 has been rocked to latching position by pin 223 during this cycle a projection 242 on cam 239 encounters cam follower 238 and rocks it clockwise. The arm 236 is likewise rocked clockwise through link 237 and a pin or roller 235 on the rearward extension of the arm presses on the supporting structure of the armature 217 and rocks the structure clockwise to the position which it would normally assume if the magnet 218 were energized. This releases the member 215 and permits the toggle 214 to break moving the latch 213 out of the path of the tail piece of pawl 212 and the clutching engagement between the discs 196 and 198 continues for another revolution of shaft 195. During this second revolution this action is repeated; the cam follower 238 in this case being rocked by a projection 241 on cam 239 and the clutching action continues for another or third revolution of shaft 195. If at the end of this third cycle the magnet 218 is not reenergized the clutch 196-198 will disengage as there is no projection properly positioned on the cam 239 to release the arm 215 after it has been rocked to latching position by the pin 223. Considering then that the toggle 214 remains in its restored position as in Fig. 12 the leaf spring 233' fixed on toggle member 234 projects into the path of the tail piece of pawl 212 and when the tail piece encounters this spring the pawl is rocked counterclockwise causing its nose to move out of the slot 211 and releasing the clutching action between discs 196 and 198. Due to the momentum of the parts, however, the disc 198 coacts a short distance and just

before the tail piece of the pawl reaches the latch 213 a projection 243 on the disc encounters a spring pressed braking and impositive latching arm 228 whereupon its momentum is further overcome and the latch 213 encounters the tail piece of the pawl and latches it after the motion of disc 198 has practically ceased. The end of arm 228 now rides onto the trailing edge of projection 243 and forces the disc 198 to cause the tail piece of the pawl to press firmly against the latching hook of latch 213 unless it is already in this position and thereafter holds the disc 198 firmly in its rest position. It will be apparent that this construction provides a clutch of the one revolution type which performs all the functions of the prior ones but operates smoothly without shock to the several operating members.

The shaft 201 is driven from the shaft 195 by a similar clutch shown in the upper portion of Fig. 13. The operating mechanism of the clutching pawl is exactly similar to that just described and it is unnecessary to explain it in detail. It will be noted, however, that the driving member 203, fixed to the freely rotatable sleeve 208, is provided with three notches in which the pawl may engage instead of only one as is the case with the driving member 196 (Fig. 21).

The driving member 203 is driven one third of a revolution for each revolution of the shaft 195 and the driving member may stop in any one of three positions when the shaft 195 comes to rest in its home position. The provision of the three equally spaced notches insures that the shaft 201 will always start in the proper phase with the shaft 195 when the clutch magnet 245 of the clutch 202-203 is energized.

The shaft 191 is driven by a clutch 205-206 shown in the lower portion of Fig. 13 whose clutching elements are exactly similar to those disclosed in connection with Fig. 12 but which are controlled from a cam on the shaft 201 instead of by a magnet. As previously stated one element 205 of this clutch is fixed to the shaft 195 and the other element 206 is fixed to the shaft 191. The clutching pawl is released by a toggle 246 exactly similar to toggle 214 in Fig. 12 which is operated by an arm 247 provided with a hook 248 at its upper end which engages a latch on a pivoted arm 249. The arm 249 is similar in its structure and operation to the supporting structure for armature 217 (Fig. 12) and is operated by a pivoted arm 258 connected through a link 250 with a rock lever 251 whose end rides on a cam 252 fixed to shaft 201. The cam 252 is provided with a raised surface 253 which once each revolution of shaft 201 rocks the arm 251 clockwise raising the link 250 and rocking the arm 258. A rearward extension of the latter carries a pin 259 which engages the latch 249 rocking it

clockwise to release the lever arm 247. This raised portion 253 is so located on the cam 252 that in the normal rest position of the shaft 201, the toggle 246 will be broken permitting 5 the clutch elements to engage. Now as long as the shaft 201 remains stationary the clutch 205—206 remains engaged and shaft 191 rotates with shaft 195. Thus when the machine is started with no card under the upper 10 brushes the shaft 191 will make two revolutions with shaft 195 to feed the first card under the lower brushes. During these two cycles, of course, the driving element 203 rotates freely on the shaft 201 and the latter 15 does not rotate. But now if the magnet 245 is energized to engage the clutch 202—203 the shaft 201 rotates and shortly thereafter the arm 251 drops to lower portion of cam 252 permitting the latch 249 to move to latching 20 position.

During this cycle a pin 254 on the element 206 engages the offset surface 260 on the arm 247 and moves it to latching position and it is latched by latch 249. At the end of this revolution of the clutch elements 205—206 disengage and remain disengaged during the following two cycles while the end of arm 251 is still riding on the low portion of cam 252. The shaft 191 therefore does not rotate and 25 card feed is suspended during these two cycles. During the next cycle the arm 251 again rides to the high portion of cam 252 releasing the arm 260 whereupon the clutch 205—206 again engages and the shaft 191 30 again makes another revolution with shaft 195. This operation then continues providing for the rotation of shaft 191 during one out of three machine cycles as long as shaft 201 continues to rotate.

40 Card feed controlling devices

The particular clutch mechanism just described is precisely the same as that disclosed in the prior application Serial No. 185,711 45 filed April 22, 1927, and is utilized for combination hole cards of the type shown in Fig. 6. When the machine is employed for Hollerith cards it will be obvious that the feeding mechanism must be modified to insure cards 50 are fed every cycle and that the different hole spacing be taken care of. The difference in the hole spacing of the two types of cards is readily apparent by a comparison of Figs. 6 and 7 and stated dimensionally adjacent combinational holes are spaced .184" apart while for Hollerith cards the spacing is .250". It will 55 be readily seen that combinational hole cards require less movement to cover the entire field and to bring the analyzing of the successive 60 perforations in synchronism with type selecting and the differential control of the accumulator elements. At the same time while the feeding rolls should be slowed down for combinational cards while analyzing operations 65 are taking place the feeding movement

must of course then be greatly increased to quickly feed the card to the next set of brushes. The preferred means for altering the card feed for either types of card will now be explained.

As stated hereinbefore shaft 191 is driven a complete revolution to feed a single card. Fixed to shaft 191 is a gear 153 (Fig. 4) driving a gear 155 through a gear 154. Attached to the shaft which carries gear 155 is a gear 134 which in turn drives a gear 136 through gear 135. The gear 136 is loosely mounted on a shaft 137 and drives a broad pinion 138 pivotally carried by a stud 139 carried by a yoke 140 which is mounted for a rocking movement about shaft 137. To adjust the mechanism for feeding Hollerith cards the yoke is locked in the position shown in Fig. 4 by a locking pin 141 slidably mounted in the lower part of yoke 140 and adapted to register and enter a hole 142 in a member 143 rigidly secured to a stationary frame member 144. When in this position a direct drive to shaft 137 is secured since pinion 138 meshes with a pinion 145 carried by yoke member 140 which pinion meshes with a gear 146 attached to shaft 137. By a train of gears 156 (Fig. 1) shaft 137, when driven in the manner just described, drives the various feeding rollers at the proper and constant linear speed to take care of the larger hole spacing.

To accommodate the machine for feeding combinational hole cards, pin 141 is laterally adjusted to enter a hole fitted in the end of a reciprocating link 148 which is guided in its movement by an arcuately slotted guide plate 149. Link 148 is articulated to an arm 150 whose roller 151 engages the race of a box cam 152 attached to shaft 191. During each revolution of box cam 152 link 148 will be reciprocated thus reciprocating yoke 140 causing pinion 138 to roll over gear 136 while the latter is driving the gear 136 and also causing pinion 145 to roll over gear 146 while the latter is also being driven. It will be apparent that such rolling movement causes an increase in angular velocity when link 148 is moved to the left and as link 148 is moved back to its normal position shaft 137 is driven at a diminishing angular velocity. The race of box cam 152 is so designed as to compensate for the smaller hole spacing during analyzing of the card. After this feeding movement, the shaft 191 is then idle for two cycles followed by the completion of the rotation of cam 152.

It should be observed that the race of box cam 152 is so designed as to feed the card the remainder of its feeding movement at an increased linear speed to feed the card the proper distance to the next set of brushes and that the increased linear speed is also timed to occur to feed a card from the stack 160 to the first set of brushes.

adjusted to provide for feeding Hollerith cards during every machine cycle will be taken up later, particularly in connection with the circuit diagram.

5 *Printing mechanism*

The printing mechanism is shown generally in Fig. 1 and consists of a drum 61 which, as previously stated, is rotated constantly as long as motor 50 is in rotation. 10 This drum carries a plurality of pivoted type carriers 265 (Fig. 14) on each of which are mounted a plurality of type 266, placed one below the other, three being the usual number of type on a type bar. Coacting with each type carrier is a locking cam 267 which through a suitable gear train (not shown) is rotated in synchronism with the drum, each cam making one revolution for each revolution of the drum. The printing 15 mechanism and operation will be explained in connection with Fig. 14. Each carrier is provided with a cam surface 268 with which the cylindrical surface of its locking cam 267 engages, as indicated in connection with 20 the type carrier to the extreme left, except when the type carrier is in printing position or in other words when it is opposite the platen 62. In this printing position a suitable notch in the locking cam 267 is presented to the type carrier to permit it to be 25 rotated about its pivot if it is selected for printing at this time. The type are selected for printing by a call magnet 269. The type carrier is actuated by a printing finger 30 270 having a hook 271 at its end adapted to engage an extension 272 on the type carrier if the printing finger is rotated about its pivot and this engagement, owing to the inertia of the rotating drum 61, forces one of 35 the type on the carrier against the platen to effect printing on a record sheet carrier thereby.

The finger 270 is normally held out of 40 printing position by a compression spring 273. A pivoted lever 274 has a dog 275 pivoted to one of its arms which normally rests against the tip of the printing finger 270. The dog is free to rotate about its 45 pivot but is urged in a clockwise direction against suitable stops by spring 276. Another arm of the lever 274 is normally engaged in a notch 277 in the pivoted latch lever 278, the latch lever being urged to 50 latching position by a spring 279. The finger 270 is normally in non-selecting position and the latch lever in latching position as illustrated. Energization of the magnet 269 attracts its armature 284 and an extension 285 thereon forces a call rod 285 to the right as shown in Fig. 14 in which position the rod rocks the lever 278 against the action of its spring and releases the lever 274, which under the action of a spring 286 rocks clockwise 55 causing the dog 275 to snap under the

end of printing finger 270. Shortly after this a cam surface 287 formed on the lever 274 is engaged by a projection 272 on a type carrier behind the one which is to print and the lever 274 is rocked counterclockwise. 70 The dog 275 being under the printing finger 270 thereupon rocks it against its spring 273 and forces the hook 271 into the path of the extension 272 on a type carrier which is thus called for printing. The camming action 75 between the extension 272 and the cam surface 287 continues after the proper type is actually selected for printing and the dog 275 slips from beneath the end of printing finger 270 whereupon the spring 273 returns 80 the printing finger to normal inoperative position and the latch lever 278 again engages the lever 274 and prevents its further operation until the call magnet 269 is again energized. 85

The platen is shown in full lines in one printing position and in dotted lines in its other printing positions. As previously stated it is necessary to shift the platen successively to its three printing positions so 90 that when a type carrier is rotated about its pivot the proper type will strike the platen. The mechanism for shifting the platen is also illustrated in Fig. 14. The platen 62 is journaled in a pivoted frame 290 normally held by a spring 291 so that the platen 62 assumes its upper position as shown in dotted lines. An operating lever 292 pivoted on the shaft supporting the frame 290 has one arm operatively engaging a pin 293 100 on the frame and the other riding on the surface of a cam 294. This cam through a one revolution clutch 294a controlled by magnet 295 may be clutched to the shaft 296 which through a gear train of suitable 105 ratio is connected to the driving motor of the machine so that this shaft makes one revolution for every three machine cycles. As long as the magnet 295 is energized at the proper point of the machine cycle the shaft 110 296 continues to rotate. The cam 294 is provided with three dwells each covering approximately one-third of its periphery and each at different radial distances from its center. Normally the lever arm 292 rests on the lowest dwell of the cam permitting the spring 291 to hold the platen 62 in its uppermost position. If the cam 294 is not clutched to the shaft 296 the platen remains in this position. After the cam is clutched to the 115 shaft 296 the platen 62 remains in its uppermost position during one machine cycle at the end of which the next higher dwell of the cam comes under the arm 292 rocking it clockwise to rock the frame 290 clockwise 120 until the platen 62 arrives at its intermediate position where it will remain for one machine cycle. At the beginning of the third machine cycle the end of arm 292 rides to the upper dwell on cam 294 and the frame 125 130

290 is forced to its lowermost position during this third cycle. At the end of this cycle the arm 292 rides on the lowest dwell of the cam 294 and the operation is repeated. Each 6 position of the platen as will be apparent causes a different type on the type carriers to print.

Translating mechanism.

- 10 The code of the combinational index point system by which the different characters are designated is indicated in Fig. 16. As on the usual tabulating card a portion of a card field is divided by vertical and horizontal 15 lines into horizontal rows and vertical columns. The index point positions on the card correspond to the little squares formed by these lines. The columns vertically contain six index point positions represented by the 20 letters A, B, C, D, E and F to the left of the diagram, A designating the lowest index point position, B the next highest, and so on. The alphabet, digits and other desired characters are indicated at the top of the several 25 columns. The corresponding code of perforations by which they may be represented on the card field is shown in the column directly beneath them. In this system a character may be represented by either one, two 30 or three perforations in a column. For example, the letter I is represented by a single perforation in the A position, the letter D is represented by a perforation in the C position in combination with a perforation in the 35 E position and the letter C is represented by a combination of perforations in the D, B and E positions. This code requires only six index point positions to represent all the characters in general use and two of these 40 card fields may be conveniently placed one below the other on the controlling card now in use, in effect doubling its capacity.

The present machine as will be understood from the previous description analyzes each 45 column of a card field with a single brush and the analysis is made while the card is in motion. This means that the perforations of any given combination are not analyzed simultaneously but successively and as the 50 printing and accumulating requires a single timed impulse to properly select the required type or to properly initiate the accumulating operation these successive analyses of the perforations in a given combination must be 55 set up, held temporarily and converted in a single timed operation.

The method by which this is done will be first explained generally in connection with Fig. 15 which shows a development of six 60 discs A, B, C, D, E and F corresponding to the several index point positions in Fig. 16. These discs although actually all of the same size have been represented by concentric circles in Fig. 15 for the purpose of clearly 65 showing their cooperation. The discs are

frictionally driven on a common shaft and may be shifted slightly thereon as will hereinafter be explained. The indentations in the circles represent notches in the discs and normally any character will be printed if 70 notches in the discs are aligned along the radial line corresponding to the character. The printing of any character then requires six notches to be aligned along a radial line. Notches on the discs corresponding to the 75 index point positions which are not actually involved in the combination corresponding to a character are normally aligned. For example along the radial line representing the character A notches in the F, D and C and A discs are on the radial line while notches in the E and B discs corresponding to the index point combination for the letter A are not on this line. As the card passes under the brush the brush senses the positions A, B, C 80 in order. When it encounters a perforation in the B position the disc B is shifted to bring a notch therein along the radial line corresponding to A. This is still not sufficient to select the A type for printing as the E disc still has no aligned notch. When the brush reaches the E position and encounters a perforation, the E disc is shifted on the shaft bringing a notch thereon to the radial line A 85 whereupon each disc along this radial line 90 has a notch on the radial line corresponding to A. The discs rotate continuously regardless of this relative displacement and at a given point in the cycle a suitable member drops into the aligned notches and selects the 95 printing type corresponding to the character for printing.

It will be noted that the characters are divided into three groups around the periphery of the discs, the first group consisting of all 100 the digits and the letters A, T, S and G. The second group consists of a number of special characters and the letters of the alphabet from U to Z respectively while the third group consists of the remaining letters of 105 the alphabet. The member which searches the aligned notches is placed in a definite location past which each group moves during a separate machine cycle. Thus three 110 machine cycles are required to pass the three groups past the searching member. If the letter A has been sensed as just explained, causing alignment of notches in the six discs along the radial line A, when this line reaches the searching device the latter drops into the 115 notches for an instant while the discs are in motion and operates suitable mechanism to energize the proper call magnet to print the letter A, this operation, of course, being a single timed operation adapted to the selection of the type on the printing drum.

The printing drum makes three revolutions for each revolution of the translator discs and the upper type on the carriers correspond to the characters in the first group. During 120 130

- one cycle then if any combination on the card represents one of the characters in this first group the type carrier on which the type is located will be selected during this cycle.
- 5 During the second cycle the platen goes to the intermediate position to select the middle type on the carriers which correspond to the second group and the aligned notches in this case will select the proper type carriers to
- 10 print characters of the third group. During the third cycle the platen goes to its lower-most position to effect printing of any characters in the third group and aligned notches in this group will select the carriers during
- 15 this cycle. At the end of the three cycles any character represented in the card which has been analyzed will be printed and any digit represented may be entered into the accumulators and accumulated.
- 20 The translators which are diagrammatically represented by the notched circles in Fig. 15 are illustrated in detail in Figs. 17 to 21 inclusive. Referring to Fig. 17 a complete translator for a denominational order is
- 25 shown driven from the shaft 54 (see Fig. 1). The translator comprises generally two sets of discs represented at 299 and 300 which are driven with a one to three ratio from the shaft 54. The discs 300 correspond to the
- 30 notched circles A, B, C, etc. in Fig. 15 and are frictionally mounted on a sleeve 301 freely rotatable on a stud 302 (see Fig. 18). The sleeve 301 is provided with a flange 325 and the discs A, B, C, etc. are separated by friction discs 303 and the whole assembly is mounted on the sleeve and held against the flange by a retaining plate 326. The plate 326, the friction discs 303 and the discs A, B, C, etc. are perforated to fit over tapped studs 327 fixed in the flange. The friction discs 303 are provided with holes closely fitting the studs so that there is no relative movement between them and the sleeve, while the studs pass through slots 305 in the discs
- 35 A, B, C, etc. (see Fig. 17) so that the latter discs, while they will always rotate with the sleeve are permitted a limited movement relative thereto. Suitable machine screws 331 coacting with internal threads in the studs 327 hold the assembly of discs firmly on the sleeve but permit ready removal if it becomes necessary to replace any disc. The sleeve 301 is similarly held on the stud 302 by a screw 332. The limited movement of the discs 300
- 40 on the sleeve 301 is utilized to align the notches in the discs as explained in connection with Fig. 15. The discs 299 (Fig. 17) are similarly mounted on a stud 306 but these discs are rigidly fixed to their supporting sleeve so that there is no relative movement between them. Each of these discs also corresponds to one of the index point positions A, B, C, etc. and each is provided with a single extension 307 (Fig. 17) which extensions correspond in position to the position
- 45 of the machine in analyzing the index point position to which it corresponds.
- The translator is controlled by a single magnet 310 whose armature is pivoted on a plurality of pins 311 and urged away from the magnet core by a spring 312. A lever 313 corresponding to each of the discs 299 and having a downward extension 314 extending into the path of the extension 307 on the corresponding disc 299 is supported through a pin and slot connection by a cross member 315', the pin and slot permitting the central portion of this lever to move freely up and down in response to actuations by the extensions 307. One end of each of these levers is provided with an upward extension 315 which extends through a perforation 318 in the supporting structure of the magnet armature (Figs. 17 and 20) while the other end of the lever comprises a latch 319 for an operating pawl 320 and normally holds this pawl in inoperative position. As long as the armature remains in the position shown in Fig. 17 the left end of the levers 313 are free to rise and the coaction of the extensions 307 with the levers does not release the latches 319. When the armature 316 is attracted by the magnet 310 in response to an index point perforation in a card column the upward extension 315 is directly below a portion of the armature structure which forms a pivot for it as shown in Fig. 19. At the time of energization of the magnet then any extension 307 which moves under the downward extension 314 of its corresponding lever 313
- 50 rocks the lever upwardly about the extension 315 as a pivot releasing the pawl 320. The magnet 310 is energized instantaneously for each index point encountered by the analyzing brushes. Consequently during the passage of the entire card any levers 313 corresponding to the index point positions encountered by the brushes will be raised to release their operating pawls 320. A spring 321 fixed to a bracket 322 on the frame of the translator unit normally forces the central portion of levers 314 downwardly.
- An operating pawl 320 cooperates with each of the discs 300. Any pawls which are released during the cycle ride on the periphery of the disc as shown in Fig. 19 until they reach a notch 323 in their discs whereupon each is actuated by an individual spring 338 to engage a deep notch 323 as indicated in Fig. 20. After the necessary pawls 320 have been released and engage their notches 323 in this manner a bell crank 328 is rocked by a projection 329 on a disc 330 also driven by the gear 309 and this bell crank rocks the pivoted supporting structure of the pawls 320 against the action of a spring 335 as shown in Fig. 20. This causes each operating pawl 320 which has engaged a notch 323 in its associated disc to shift the disc about the sleeve 301 in a clockwise direction to the
- 55 90 95 100 105 110 115 120 125 130

end of its travel as limited by the slots 305. The discs 300 rotate during this operation and after it, so that after the shifting all the discs continue to rotate in their new relationship. This shifting, of course, aligns the proper notches as explained in connection with Fig. 15 so that somewhere around the periphery of the disc there will be a series of aligned notches in each of the discs 300 and, 10 of course, for any given card column there will only be one series of aligned notches as only one character can be represented in the column.

The discs continue to rotate until the 15 aligned notches reach a searching mechanism indicated at 340 (Figs. 17 and 21) which consists of a pivoted structure 341 carrying at one end a pivoted member 342 which is spring-pressed into engagement with the periphery of the discs 300. When a series of aligned notches is presented to the member 342 a bevelled edge 343 on the latter engages the notches and the member 342 is rocked about its pivot on the member 341 causing the 20 latter to rotate clockwise as indicated in Fig. 21 whereupon an extension 345 on structure 341 forces a rod 346 to the left as indicated in Fig. 21. This rod 346 (see Fig. 17) when forced to the left closes a pair of contacts 347 25 which are included in the proper printing call 30 magnet circuit to select the proper type.

It will be understood that the rotation of the discs 300 is properly timed with the rotation of the drum so that any character manifested by aligned notches will not only select the proper type carrier but will select it during the machine cycle in which the platen is in proper position to receive the type representing the character.

40 After the discs 300 have practically completed a revolution a pawl 350 (Fig. 17) is engaged by an extension 351 on a disc also mounted on the sleeve 301 and rocked clockwise to force an extension 352 on the pawl 45 into a bevelled notch 353 on the discs 300 which shifts all discs back to their normal position in which no complete line of notches is present. The translator is then in condition to set up and translate another combinational hole character.

Circuit diagram

The general operation of the machine will now be explained in connection with Fig. 2 55 of the drawings. In connection with this explanation it should be borne in mind that during normal running conditions a card of the combinational type is fed beneath the adding brushes during one machine cycle and its 60 combinational holes sensed to effect a set up in the translator. This set up is held on the translator during three printing cycles. During the first printing cycle the translator is searched for set ups corresponding to type 65 of the first or upper group. During the sec-

ond cycle the translator is searched for set ups corresponding to type of the second or intermediate group and during the third cycle for set ups corresponding to type of the third or lower group.

This sequence of feeding and printing cycles is effected through the two card feed clutches described above which are represented in Fig. 2 at A and B, A being the clutch controlled by the magnet 218 and B being the clutch controlled by the magnet 245. In the diagram the upper or control brushes 167 are connected to sockets on a plug board 355 while the lower brushes 168 are connected to similar sockets 406 on the plug board.

A plurality of counters have been indicated at 364 and 365 which are of the type disclosed in my copending application Serial No. 147,960, filed November 12, 1926, whose counter magnets 366 are connected to sockets on the plug board 355. The machine is started in operation by one of the starting timers D and E and is controlled when total printing is desired by the total timer F. The operation of all these devices are fully explained in my copending application above referred to and will be very briefly described in the present case.

The translators are indicated at 368 having their control magnets 310 each connected to an individual socket on the plug board 355 through which any one may be plugged to any desired analyzing brush 168. The printing control contacts 347 of the translators are connected to sockets 375 through which by suitable jumpers 376 may be connected to any desired printing magnet 269. A plugging arrangement to be described also permits any counter to be associated with any lower analyzing brush for control thereby and any printing magnet to be associated with any lower analyzing brush for listing.

The motor 50 which drives the mechanical elements of the machine is controlled by switch 377, closure of which connects the motor directly to the supply mains 378 and 379 of which the former has been designated + and the latter -. Card feed may be initiated by depressing the start key ST whereupon a circuit through either the E starting coil 380 or the D starting coil 116 will be completed. The selection of the D or E timer depends on the position of the card lever 381 which, when no cards are under the upper brushes, assumes the position shown in the drawing closing the contacts 382 and opening the contacts 383. In this case the D timer will be selected. The D timer controls the machine through several initial tabulating cycles permitting the first card to feed from the card magazine beneath the upper or control brushes 167 during one machine cycle and to the lower brushes 168 during the succeeding cycle.

If there is a card under the upper brushes when the start contacts ST are closed, the card lever 381 is moved to its alternative position closing the contacts 383 and opening the contacts 382. In this case the E timer will be selected. The E timer controls machine operation to feed the card which is under the upper brushes to the lower brushes. The total or F timer is controlled by the contacts 385 which are closed by the A card feed clutch elements whenever they are disengaged, and opened when they are engaged. A key 386 permits manual control of the total timer. If this key is closed when the A clutch disengages at the end of a card group the F timer starting coil will be automatically energized through a circuit extending from line 378 through key 386, contacts 385 to the total timer starting coil 387 and through return wire 384 to the negative side of the line 379. The contacts of the total timer are operative during a plurality of machine cycles to selectively close certain total printing switch bars during certain cycles so that printing with reset or without reset may be effected from any desired counter element.

It may now be assumed that a stack of cards from which it is desired to list data have been placed in the magazine and that no card is under the upper brushes. The upper card lever contacts 415 will now be opened preventing energization of the B clutch magnet 245 and the upper card lever 381 will be in the position shown in the drawing, closing contacts 382 to select the D timer for starting. Depression of the start key ST will complete a circuit through the D timer starting coil as follows: from line 378 through start key contacts ST, thence through contacts 382 to D starter coil 116 and through common return 384 to the other line 379. The D timer contacts D-2 close and remain closed for two full cycles, closing a circuit through the A clutch magnet 218 as follows: from line 378 through wires 390 and 392 to contacts D-2, closed at the proper point in each cycle thence through wire 393 to A clutch magnet 218, and through switch lever 420 to contact point 421 (for combination hole cards) regular contact R-20, wire 391 to the other side of the line 379.

The clutch magnet 218 being thus energized for two cycles during the first of which the secondary clutch magnet 245 cannot be energized owing to the open condition of upper card lever contacts, the clutch 205-206 (referring to Figs. 9 to 13) remains engaged as well as the clutch 196-198 and the first card from the magazine feeds to the upper brushes and the lower brushes during successive machine cycles. When this first card reaches the upper brushes the upper card lever contacts 415 close and a circuit through the secondary clutch feed magnet 245 is completed as follows: from line 378 through contacts

415, magnet 245, cam contacts CFA-2 and R-20, closed synchronously at the proper time in the cycle, and through common return 391 to the other line 379. The energization of the B clutch magnet 245 concurrently with the operation of the A clutch effects suspension of the combinational lever card feed for two cycles after each card is analyzed by the lower brushes as explained in connection with Figs. 17 to 21.

The B clutch, of course, provides for the two extra printing cycles required for the card under the lower brushes but at the end of these as neither the control circuit for the A clutch magnet 218 nor the control circuit for the B clutch magnet 245 makes, card feed ceases and the machine either stops or takes a total depending on its setting.

If the machine is to be started with a card under the upper brushes, meaning that upper card lever contacts 415 and 383 are closed, depression of the start key ST energizes the starter magnet 380 of the E timer, the circuit being similar to that traced above for the D timer starter magnet. Also in this case the B clutch magnet 245 is also energized owing to the fact that card lever contacts 415 are closed and the card under the upper brushes feeds to the lower brushes for analysis after which card feed is suspended for two cycles.

Each card is analyzed as it passes the lower brushes 168 and every perforation in a given column energizes the control magnet 310 of one of the translators 368. The energizing circuit extends from line 378 through wire 403, regular contacts R-21, controlled as usual by a dentated wheel, contacts CFB-10, wire 404 and lower card lever contacts 173 to conducting cylinder 170, thence through the card perforations to one of the analyzing brushes 168 and through the associated socket 406 and a suitable jumper 402 to a socket 407 connected to the control magnet 310. One or more energizations of this magnet sets up a combination on the translating discs which during one of the three machine cycles associated with the particular card effects closure of the contacts 347. Closure of these contacts establishes a circuit through suitable jumpers 376 to the corresponding printing call magnet 269 to select the proper type for printing. This circuit extends as follows: from line 378 through wire 401 to contacts 347, thence through wire 404 to socket 375 and through jumper 376 and wire 409 to printing magnet 269 which is connected to the negative line 379.

As long as the B clutch is in operation the clutch magnet 295 of the platen shift mechanism is energized once every three cycles to provide for shifting of the platen. The operating circuit for this magnet is controlled by the contacts CFB-1 and extends from line 378 through wire 399, contacts CFB-1,

magnet coil 295 and wire 401 to negative side of the line 379. It will be understood from the preceding explanation that the energization of the printing call magnet circuit for each combination is timed not only to select the proper type carrier but to select it during the cycle in which the platen is in position to receive an impression from the type corresponding to the set-up in the translator.

10 While the cards are being fed through the machine the letters of the alphabet represented thereon can be printed and the numerals represented can be listed and entered into the accumulators.

15 The circuit diagram just described assumed that the machine has been conditioned for feeding and analyzing combinational hole cards. Certain adjustments are necessary to make the machine responsive to regular Hollerith cards and digressing it will be remembered that the plug board connections disclosed are such that each electrical impulse caused by a perforation on a card will energize the translating magnets 310 which, 25 in turn, close contacts 347 to energize printing magnets 269 to select the proper type.

When regular Hollerith cards are used the translators are entirely disconnected so that impulses responsive to card perforations will 30 directly energize printing magnets 269 or adding magnets 366.

It will be noted that in the position of the parts shown switch bar 70 directly connects sockets 375 to the connections 500 leading to 35 adding magnets 366 by switch blades 501 carried by the switch bar but when said switch bar is moved to the left by bell crank 502 switch blades 501 connect the adding magnets to sockets 406 by jumper connections 503. In this manner impulses due to card 40 perforations of Hollerith cards are directly transmitted to the adding magnets. When switch bar 504 is moved by bell crank 506, switch blades 505 carried by the switch bar 45 disconnect sockets 407 from the wires 404 leading to the translator magnets 310. Switch bars 504 and 70 are connected together for a simultaneous mechanical movement by handle 507 by a link 508 connecting bell cranks 502 and 506. In order that impulses responsive to card perforations in regular Hollerith cards may directly reach 50 printing magnets 269 the jumper connections 376 are shifted from the position shown so 55 that one end of each terminates at plug sockets 406.

In the manner just described impulses reaching printing magnets 269 will cause the selection of the numerals carried by the revolving drum 61 during each card feeding cycle and adding elements 120 will be actuated a commensurate amount.

When the machine is to be controlled by regular Hollerith cards it is apparent that in 60 order to have cards fed each machine cycle

that the "B" clutch 202-203 be rendered inoperative and the preferred means for accomplishing this comprises the switch lever 420, (Fig. 2) which as stated before, is adjusted to contact point 421 for combinational cards so that an impulse to magnet 245 is controlled by synchronously timed cam contacts R-20 and CFA-2. The cam controlling contacts R-20 is controlled by one of the R cams (see Fig. 1) carried by the regular driving shaft of the machine while the cam controlling contacts CFA-2 is controlled by one of the CFA cams carried by the clutch shaft 195.

When switch lever 420 is adjusted to contact point 422 for Hollerith cards it will be noted that the circuit for A magnet 218 is now through regular cam contacts R-10. To prevent the energization of magnet 245 through contacts CFA-2 and R-20 to line 378 by wire 391 the shaft 195 carrying contacts CFA-2 is clutched to shaft 53 at a different time and in the present instance this timing is controlled by cam contacts R-10 which make at a different time than cam contacts R-20. Cam contacts R-10 will therefore cause magnet 218 to be energized at a time when the clutch elements will engage a notch 211a (Fig. 12) instead of notch 211 and as a result cam contacts CFA-2 and R-20 95 will now make disynchronously. Since the revolutions controlling shaft 201 will be idle shaft 191 will operate continuously to feed cards uninterruptedly during every machine cycle.

It will also be recalled that all the numeral type are included in the first group which comprises the upper type on the carriers and hence, during feeding of Hollerith cards, the platen should remain in its uppermost position where any type carrier selected will effect printing from its upper type. During the feeding of regular Hollerith cards the contacts CFB-1 (Fig. 2) are open and the platen control magnet 295 is not energized 100 permitting the platen to remain in its uppermost position during feeding of Hollerith cards.

While there has been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore, to be limited only as indicated by the scope of the following claims.

I claim:

1. In a tabulating machine including means for feeding combinational or Hollerith single hole record cards to an analyzing mechanism, data indicating devices controlled by said

analyzing mechanism and means for adjusting said feeding means to compensate for the unequal hole spacings in combinational and single hole record cards.

5 2. In a tabulating machine including means for feeding combinational or Hollerith single hole record cards to an analyzing mechanism, data indicating devices controlled by said analyzing mechanism and means for selectively adjusting said feeding means whereby said analyzing means is responsive to either combinational or single hole record cards.

10 3. In a tabulating machine including means for feeding combinational or Hollerith single hole record cards to an analyzing mechanism, data indicating devices controlled by said analyzing mechanism and means adjusted preliminarily to an operation of the machine for selectively adjusting said feeding means 20 to compensate for the unequal hole spacings in combinational and single hole record cards and to render said analyzing means responsive to either type of record cards.

25 4. In a tabulating machine comprising in combination, means for feeding record cards of the single or combinational hole type, driving means therefor, and means for varying the driving means to compensate for the unequal hole spacings of the different types of record cards.

30 5. In a tabulating machine comprising in combination, means for feeding record cards of the single or combinational hole type, driving means therefor, and means for varying the 35 driving means during the feeding of combinational hole cards to compensate for the unequal hole spacing.

35 6. In a tabulating machine comprising in combination, means for feeding record cards of the single or combinational hole type to analyzing means, driving means for said feeding means, selective means whereby said analyzing means is made responsive to either single or combinational hole record cards, and 45 means for varying the driving means to compensate for unequal hole spacings of the different types of record card.

50 7. In a tabulating machine including in combination, means for periodically feeding a record card during a plurality of machine cycles, analyzing means responsive to said cards, and means for adjusting said feeding means for feeding cards every machine cycle to said analyzing means.

55 8. In a tabulating machine including in combination, means whereby record cards are fed intermittently during machine cycles, analyzing means responsive to said cards, and means for adjusting said feeding means 60 whereby cards are fed continuously and in correspondence with machine cycles to said analyzing mechanism.

65 9. In a tabulating machine including in combination, analyzing means responsive to either single or combinational hole record

cards, means for feeding record cards to said analyzing means, and selective means for adjusting said feeding machines whereby record cards are fed periodically or synchronously with respect to machine cycles to said analyzing means.

70 10. In a tabulating machine including in combination, analyzing means responsive to single or combinational hole record cards, said analyzing mechanism requiring a plurality of cycles of operation for completely analyzing combinational holes and a single cycle of operation for completely analyzing single hole record cards, and selective means for controlling operating cycles whereby said analyzing means is rendered responsive to either single or combinational hole record cards.

75 11. In a tabulating machine comprising a translating mechanism responsive to index points in successively fed record cards and adapted to convert combinational index point readings into a single differentially timed operation, adding and printing magnets controlled by said translating mechanism, and switching means for disconnecting said translating mechanism whereby said index points directly control said adding and printing magnets.

80 12. In a tabulating machine comprising in combination, means for feeding single or combinational index point record cards, a translating mechanism adapted to convert combinational index point readings into a single differentially timed operation, adding 85 and printing magnets, and selective means whereby said adding and printing magnets are controlled directly by the index points of single index point record cards or by combinational index point record cards through 90 said translating mechanism.

95 13. In a tabulating machine comprising in combination, means for feeding record cards to an analyzing mechanism periodically with respect to machine cycles, analyzing mechanism responsive to said cards operable during a plurality of machine cycles for completely analyzing a record card and means for adjusting said feeding means whereby record cards are fed during each machine 105 cycle and analyzed concurrently.

110 14. In a tabulating machine including in combination, an analyzing mechanism for sensing perforations in successively fed record cards, means for feeding record cards to the analyzing mechanism and means for controlling said feeding means whereby record cards are fed during card feeding cycles at a variable linear speed.

115 15. In a tabulating machine including in combination, an analyzing mechanism for sensing perforations in successively fed record cards, means for feeding record cards to the analyzing mechanism and selective means 120 125 130

- for controlling said feeding means whereby record cards are fed during card feeding cycles at a constant or variable linear speed.
16. In a tabulating machine including in combination, an analyzing mechanism for sensing perforations in successively fed record cards, means for feeding record cards to the analyzing mechanism and means for controlling the feeding means whereby record cards are fed at a constant linear speed while the perforations are being sensed and at a relatively increased linear speed thereafter.
17. In a tabulating machine comprising in combination, an analyzing mechanism comprising brushes adapted to sense perforations in successively fed record cards, means for feeding record cards, and means for controlling said feeding means whereby cards are fed at a constant linear speed while card perforations are being sensed and to said brushes at a relatively increased linear speed.
18. In a record controlled printing machine comprising a plurality of type carriers provided with numeral type similarly located thereon and alphabet type located in several different positions thereon, a platen, means for relatively shifting the platen and type carriers to permit printing from type selected by record cards of the combinational hole type whereby numeral or alphabetical characters may be printed, and means for suspending the platen shifting operation as an incident to type selection controlled by record cards of the Hollerith type whereby numeral characters only are printed during listing operations.
19. In a tabulating machine comprising in combination, means comprising a pair of feeding rollers for feeding different types of record cards one type having its index points differently spaced from the other, driving means therefor, and means interposed between said driving and feeding means whereby said rollers are variably driven to feed record cards of one type.
20. In a tabulating machine comprising in combination, a pair of feeding rollers for feeding record cards of two distinct types one type having its index points differently spaced from the other, driving means for invariably driving said feeding rollers to feed record cards of one type and means interposed between said driving and feeding means whereby said rollers are variably driven to feed record cards of the other type.
21. In a record controlled printing machine comprising a plurality of numeral type similarly located thereon and alphabet type located in different positions thereon controlled by distinct types of record cards having index points representing either alphabet or numeral characters, a platen, means for shifting the platen relative to said type carriers to permit printing from the selected type, and means for suspending the platen shifting means for printing only from the numeral type when the machine is controlled by the type of cards representing by their index points only numeral characters.
22. In a tabulating machine comprising data indicating elements adapted to be adjusted in accordance with the index points of one type of cards, an analyzing mechanism for controlling the adjustment of said elements and means whereby said analyzing mechanism is rendered responsive to adjust said indicating elements in accordance with record cards of a different type.
23. In a tabulating machine comprising data indicating elements adapted to be adjusted in accordance with the index points of one type of cards, an analyzing mechanism for controlling the adjustment of said elements and means adjusted preliminarily to an operation of the machine whereby said analyzing mechanism is rendered responsive to adjust said indicating elements in accordance with record cards of a different type.
24. In a tabulating machine comprising an analyzing mechanism controlled by record cards of distinct types, and selective means for rendering said analyzing mechanism responsive to record cards of either type.
25. In a tabulating machine comprising an analyzing mechanism controlled by record cards of distinct types, and selective means adjustable preliminarily to an operation of the machine for rendering said analyzing mechanism responsive to record cards of either type.
26. In a tabulating machine comprising an analyzing mechanism controlled by record cards of the Hollerith or combinational hole type, and selective means for rendering said analyzing mechanism responsive to record cards of either type.
27. In a tabulating machine comprising an analyzing mechanism controlled by record cards comprising two distinct types varying in the spacing of their index points, and selective means for rendering said analyzing mechanism responsive to either type of record card.
28. In a tabulating machine comprising an indicating device adapted to represent data in accordance with index points spaced apart on a record card, an analyzing mechanism responsive to said index points for adjusting said indicating device in conformity with the index point representation and selective means for rendering said analyzing mechanism responsive to record cards that differ in index point spacing.
29. In a tabulating machine comprising an element adapted to be set to indicate a character represented by one of a plurality of spaced index points of a record card, and means whereby said element is set to indicate

a character represented by one of a plurality of differently spaced index points of a record card.

In testimony whereof I hereto affix my
5 signature.

FRED M. CARROLL.
